UNITED STATES PATENT OFFICE.

STEPHEN M. GRISWOLD, OF BROOKLYN, NEW YORK.

DESIGN FOR A FLOWER-HOLDER.

SPECIFICATION forming part of Design No. 26,631, dated February 16, 1897.

Application filed January 9, 1897. Serial No. 618,655. Term of patent 14 years.

To all whom it may concern.

Be it known that I, STEPHEN M. GRISWOLD, a citizen of the United States, residing at Brooklyn, in the county of Kings and State 5 of New York, have invented a new and original Design for a Flower-Holder, of which the following is a specification, reference being had to the accompanying drawings, forming a part thereof, in which—

5 Figure 1 is a perspective view of a flower-holder embodying the features of my design, and Fig. 2 is a rear elevation of the holder. The design consists of twin loops A and B, one being a continuation of the other. The 5 loops are side by side and taper from one end in direction of the opposite end. The said loops are connected at their narrower ends,

and their wider ends are curved or flared outwardly in opposite directions. The space C between the loops is practically that of an 20 ovoid, the contracted portion being at the flaring end or mouth D of the holder. The space E within one loop connects with a similar space in the opposing loop at the narrower or connected ends of the loops, as shown 25 in Fig. 1. A pin F is pendent from one of the said loops.

I claim—

The design for the flower-holder herein shown and described.

STEPHEN M. GRISWOLD.
